UNITED STATES PATENT OFFICE.

JOHN M. MORRISON, OF PLATTSBURG, NEW YORK.

SWITCH-LOCK.

1,381,732.

Specification of Letters Patent. Patented June 14, 1921.

Application filed November 2, 1920. Serial No. 421,216.

To all whom it may concern:

Be it known that I, JOHN M. MORRISON, a citizen of the United States, and a resident of Plattsburg, in the county of Clinton and 5 State of New York, have invented a new and Improved Switch-Lock, of which the following is a full, clear, and exact description.

In connection with switches, and more 10 particularly track switches, it is well appreciated that numerous accidents have occurred, where a switch has been thrown sufficiently to indicate that the same is open or closed, subsequent to which incident to the 15 jars of a train passing over the same, or other reasons, the switch has been released resulting in the derailment of certain of the cars of the train.

In view of this danger, rules have been 20 enacted which compel the association of a pad lock to a switch lever, to prevent any movement of the same after it has once been completely thrown, unless the pad lock is removed.

25 Numerous difficulties have been experienced in the use of this type of lock, in that the same are exposed to the action of the elements, and a great temptation exists on the part of trainmen, where the key has been lost, to destroy the pad lock, which 30 may readily be accomplished by striking the same with a hammer, subsequent to which the switch throw lever may be operated, as desired.

35 With this in view, I have constructed a lock which is incapable of being tampered with by brakemen, and in which it will be impossible to effect a withdrawal of the key operating such lock, until the switch has 40 been completely thrown, and locked in position.

A further object of my invention is the construction of a device of this nature, which should cause the actuation of a sema- 45 phore to indicate the condition of the switch, should the same be other than completely thrown.

Thus it will be impossible for a train or yardman to effect a removal of the key from 50 the lock without effecting a complete throwing of the switch, and relocking of the same.

Also it will be seen by means of my improved device, that even although an operator should neglect the removal of the key, 55 assuming that the switch had not been completely thrown, and he had overlooked the

withdrawal of the key, that this dangerous condition of the switch would be immediately indicated to the engineer of a train.

Further embodiments of my invention 60 will appear from the annexed specification and drawings, in which latter,

Figure 1 is a side view of a semaphore switch post of the type utilized in connection with my improved type of switch. 65

Fig. 2 is an enlarged sectional side view showing the arrangement of the parts of my lock, the switch being completely thrown, and the lock guarding against any movement of the parts. 70

Fig. 3 is a fragmentary sectional side view showing the lock in open position, and the switch parts moving to the position at which the switch may be thrown.

Fig. 4 is a similar fragmentary sectional 75 side view showing the parts in a more advanced stage than that indicated in Fig. 3.

Fig. 5 is a front view of the lock.

Fig. 6 is a plan view of the base of the 80 semaphore switch post.

Fig. 7 is a sectional side view showing in detail one of the parts of the lock, and

Fig. 8 is a front view thereof.

In these views the reference numeral 10 indicates the column or base commonly associated with the switch, and of any suitable type, which connects the switch semaphore 11, also of any convenient type mounted upon the rotatable shaft 12, the lower end of which extends into the base 90 10 in the usual manner.

Also in the conventional manner, a switch 95 thrown lever 13 is provided, which latter serves to effect any throwing of the switch. The base 10 includes, also in the conventional manner, a hollowed portion within which the parts, operating to throw the switch and to lock the same are positioned.

In this connection, it is to be noted that the shaft 12 conveniently mounts and is secured to a plural faced block 14 provided with outwardly extending trunnions 15, one upon each of its faces, the block 14 being adapted to seat in a recess 16, having a number of faces corresponding to that of the 105 number of faces of the block 14, and being also provided with supplemental recessed portions 17, in which the trunnions 15 are adapted to seat.

Thus to throw the switch, it is necessary 110 to primarily rock the lever 13 downwardly around its points of pivotal support 18,

This will naturally result in an elevating of the shaft 12, together with the block 14, which operation, if continued, will permit the block 14 to entirely clear the recess 16, 5 subsequent to which, upon a thrust being imparted upon the outer end of the lever 13, the shaft 12 and its associated parts may be turned to effect an operation of the switch.

10 It will be seen, however, that upon the switch being operated, that it will be necessary to effect a release of the lever 13, and assuming that the parts are in their proper position, it will further be appreciated that 15 the block 14 will again seat in the recessed portion 16.

To now provide means which will serve to prevent any raising or turning of the shaft 12, other than upon the part of a person authorized to perform this operation, and provided with a suitable key, I conveniently employ a lock of any suitable character, which serves to effect a rotation of a bolt upon the lock being actuated, by means 25 of the proper key 19. This bolt preferably includes a circular body portion 20, provided with guiding grooves 21 serving to prevent any lateral motion, the rear portion of the bolt being U shaped in cross section, as has 30 been indicated by the reference numeral 22.

Thus upon the parts being in the position illustrated in Fig. 2, will be seen that a lifting of the shaft 12, by means of the lever 13, will effectually be precluded by virtue of 35 the fact that the trunnion 15 will project into the U shaped rear portion 22 of the bolt, and be caused to engage, upon an upward pull being exerted, on the shaft 12, the base portion of this U shaped portion, thus effect- 40 ually preventing a lifting action, which will permit the block 14 to move clear of the recess 16.

Reference is now had to the inverted U shaped rear portion 22 thereof. This will 45 obviously permit of the shaft 12 and block 14 being lifted in view of the fact that the trunnion 15, adjacent the bolt is free to move upwardly. Subsequent to this lifting, the switch may be operated in the usual manner 50 to effect a throwing of the same, and upon the parts reaching their normal position, it will be obvious that the operator may actuate the bolt to return all of the parts of my improved lock to the positions shown in 55 Fig. 2.

To now provide means which will serve to operate a semaphore at a point remote from the lock thus provided, and at the same time to clearly indicate to an operator of 60 the switch that the same is not completely thrown, it will be noticed, that an opening 23 is conveniently provided through the base of the U shaped portion 22 of the bolt. A secondary bolt 24 is associated with the base 65 10. A spring 25 co-operates with the head

26 of the bolt 24 to serve to project the same.

It will also be noted, that insulation 27 is provided around the bolt 24, and the bolt lock, and that wires 28 are attached to each 70 of these members. Also the block 14, when extending properly into the recess 16, bears against the head 26 to effect a depression of the same against the action of the spring 25.

Thus upon the parts being moved to the 75 position indicated in Fig. 3, and a lifting of the shaft 12 being effected, it will be obvious that the bolt 24 will be permitted to be projected upwardly so that the reduced portion 28 of the same may extend into the 80 opening 23 of the U shaped portion 22 of the lock bolt. This obviously will close the circuit and permit current to flow through the wires 28 to actuate any suitable type of signaling device, such as a semaphore, etc. 85

Also by virtue of the reduced portion 28 of the bolt 24 firmly engaging the lock bolt, it will be seen that any rotation of the latter may not be effected until the block 14 has been permitted to seat within the recess 16, 90 which will effect a rotation of the bolt 24, thus disengaging the same from the U shaped portion 22 of the first named bolt to permit a rotation of the latter.

From the foregoing, it will be appreciated 95 that I have constructed a switch lock, which is susceptible to variation, to meet the requirements of any desirable type of switch, and in which it will be virtually impossible to lock the switch until the parts of the same 100 have been completely thrown. It will also be seen that the conventional cumbersome pad lock will be eliminated in utilizing a switch constructed in accordance with my invention, and it will further be appreciated 105 that the electrical connection established upon the parts being actuated, will serve to amply warn any authorized person as to the unsafe condition of the switch, should a person operating the same leave the parts 110 not in their proper position.

Obviously numerous modifications of structure might readily be resorted to without in the least departing from the spirit of my invention, which I claim as—

1. A switch stand, including a base formed with a recess, a shaft extending into said recess, a multi-faced block being secured to said shaft and being adapted to engage the side walls of said faces, trunnions secured to 115 and extending outwardly from said block, and means adapted to engage said trunnions for normally preventing a lifting of said block, and consequently a subsequent turning of the same.

2. A switch stand, including a base formed with a recess, a shaft extending into said recess, a multi-faced block being secured to said shaft and being adapted to engage the side walls of said faces, trunnions se- 120 125 130

- cured to and extending outwardly from said block, and a bolt formed with a U shaped rear portion, said bolt being rotatably supported within said base and being adapted 5 to have its U shaped rear portion encircling one of the trunnions fixed to said block, whereby upon said bolt being rotated to invert said U shaped portion, an elevating of the block will be precluded.
- 10 3. A switch stand, including a base formed with a recess, a shaft extending into said recess, a multi-faced block being secured to said shaft and being adapted to engage the side walls of said faces, trunnions secured to 15 and extending outwardly from said block, and a bolt formed with a U shaped rear portion, said bolt being rotatably supported within said base and being adapted to have its U shaped rear portion encircling one of 20 the trunnions fixed to said block, whereby upon said bolt being rotated to invert said U shaped portion, an elevation of the block will be precluded, and means coöperating with said bolt for preventing a rotation of 25 said bolt upon the same being turned, to permit a lifting of said block until the latter is reseated within said recessed portion.
4. A switch stand, including a base formed with a recess, a shaft extending into said 30 recess, a multi-faced block being secured to said shaft and being adapted to engage the side walls of said faces, trunnions secured to and extending outwardly from said block, and a bolt formed with a U shaped rear portion, said bolt being rotatably supported 35 within said base and being adapted to have its U shaped rear portion encircling one of the trunnions fixed to said block, whereby upon said bolt being rotated to invert said 40 U shaped portion, an elevating of the block will be precluded, and means coöperating with said bolt and actuated by said block, for preventing a rotation of said bolt upon the same being turned to permit a lifting of 45 said block until the latter is reseated within said recessed portion.
5. A switch stand, including in combination with a base formed with a recessed portion, of a shaft adapted to extend through 50 said recessed portion, a block attached to said shaft, trunnions secured to and extend-
- ing outwardly from said block, a rotatable bolt presenting a U shaped rear portion capable of over or under lying one of said trunnions to prevent an elevating of the 55 block, a secondary bolt secured to said base, a spring for slidably projecting the same, a head forming a part of said bolt and being engaged by said block, whereby to effect a retraction of the bolt against the projecting action of the spring, the base of the U shaped portion of the first named bolt being formed with an opening in the end portion of said secondary bolt being adapted to extend into the opening of the first named 60 bolt upon the latter being rotated, and the block being lifted to permit a projection of the secondary bolt, whereby to prevent a rotation of the first named bolt until the block assumes its normal position within said recessed portion.
6. A switch stand, including in combination with a base formed with a recessed portion, of a shaft adapted to extend through said recessed portion, a block attached to 65 said shaft, trunnions secured to and extending outwardly from said block, a rotatable bolt presenting a U shaped rear portion capable of over or under lying one of said trunnions to prevent an elevating of the 70 block, a secondary bolt secured to said base, a spring slidably projecting the same, a head forming a part of said bolt and being engaged by said block, whereby to effect a retraction of the bolt against the projecting action of the spring, the base of the U shaped portion of the first named bolt being formed with an opening in the end portion of said secondary bolt being adapted to extend into the opening of the first named bolt upon 75 the latter being rotated, and the block being lifted to permit a projection of the secondary bolt, whereby to prevent a rotation of the first named bolt until the block assumes its normal position within said recessed portion.
7. A switch stand, including in combination with a base formed with a recessed portion, of a shaft adapted to extend through said recessed portion, a block attached to 80 said shaft, trunnions secured to and extending outwardly from said block, a rotatable bolt presenting a U shaped rear portion capable of over or under lying one of said trunnions to prevent an elevating of the 85 block, a secondary bolt secured to said base, a spring slidably projecting the same, a head forming a part of said bolt and being engaged by said block, whereby to effect a retraction of the bolt against the projecting action of the spring, the base of the U shaped portion of the first named bolt being formed with an opening in the end portion of said secondary bolt being adapted to extend into the opening of the first named bolt upon 90 the latter being rotated, and the block being lifted to permit a projection of the secondary bolt, whereby to prevent a rotation of the first named bolt until the block assumes its normal position within said recessed portion, both of said bolts being insulated from said base, and lead wires connected to each of said bolts, whereby to effect a closing of the circuit upon the bolts engaging one with the other.

JOHN M. MORRISON.
